ARC LAMP

Elmer C. Richardson, Los Angeles, Calif., assignor
to Mole-Richardson, Inc., Los Angeles, Calif., a
corporation of California

Application August 31, 1935, Serial No. 38,749

8 Claims. (Cl. 176—51)

This invention relates to arc lamps and has particular reference to a construction for continuously feeding the positive carbon in an arc lamp employing a rotating positive carbon electrode.

In certain industries, particularly the motion picture industry, it is necessary to produce light of high intensity which must be maintained of substantially unvarying intensity and at a closely controlled spectral distribution during the taking of a picture, and particularly in photographing for production of colored motion pictures. For this purpose it is common practice to employ a carbon arc lamp of the character in which one of the electrodes, usually the positive, is horizontally mounted and adapted to be rotated about its longitudinal axis during the operation of the lamp. Employing a rotating carbon of this character, considerable difficulty is encountered in continuously feeding the carbon forwardly as it is burned away at its tip since the rate of forward motion of the carbon must be extremely small.

It has been discovered that for best results in motion picture lighting, the positive carbon electrode should be rotated at a steady rate of speed which is sufficient to maintain a symmetrically formed crater in the positive carbon as is well known in the art. The problem of coordinating such rate of rotation with the much slower rate of forward feed of the carbon has presented considerable difficulty due to the limitations of the gearing employed between the rotating mechanism and the mechanism employed for feeding the carbon and it has been particularly difficult to design into such an arc lamp a means for rapidly adjusting the position of the positive carbon manually as is often required when carbon electrodes are being replaced for operation.

It is therefore an object of my invention to provide an arc lamp of the character described wherein an axially, horizontally mounted positive carbon may be readily rotated about its longitudinal axis at a comparatively slow speed and in which mechanism is employed between the devices employed for feeding the carbon forwardly which will produce a positive, steady, slow, non-intermittent forward feeding of the carbon in accordance with the rate at which the tip of the carbon is burned away in use.

Another object of my invention is to provide a gearing between the rotating means for rotating the positive electrode in an arc lamp around its longitudinal axis, and the feeding mechanism employed for feeding the positive carbon, which

includes a spiral or scroll type of gear operating upon one or more spur gears, which spur gears engage the carbon electrode to feed the same forwardly in a non-intermittent manner.

Another object of my invention is to provide a feeding device for rotating carbon arc lamps in which the carbon is gripped between a pair of spur gears mounted on diametrically opposite sides of the carbon and in which the same spur gears engage a scroll or spiral gear mounted to be rotated about the longitudinal axis of the positive rotating electrode at a speed different from the speed of rotation of the rotating electrode.

Another object of my invention is to provide an arc lamp structure for use with a rotating carbon of the character set forth in the preceding paragraphs wherein the change speed gearing interposed between the mechanism for rotating the carbon and the scroll gear is adapted to be manually manipulated to manually adjust the positive of the carbon without disconnecting or interfering with the normal positive carbon rotating system mechanism.

Another object of my invention is to provide a system for rotating the positive carbon electrode and for feeding said electrode forward as it is consumed in the arc at a continuous non-intermittent rate of speed and to provide a means for manually adjusting the position of said rotating carbon electrode without interrupting the continuity of rotation of the positive carbon electrode, all of said functions being performed in a mechanically functioning device (as opposed to electromagnetic control).

Other objects of my invention will be apparent from a study of the following specification read in connection with the accompanying drawings, wherein

Fig. 1 is a side elevational view shown partly in section of an electrode holding and feeding assembly constructed in accordance with my invention;

Fig. 2 is a detail sectional view taken along the line II—II of Fig. 1;

Fig. 3 is a detail horizontal sectional view taken along line III—III of Fig. 1;

Fig. 4 is a rear end view of the electrode holding and feeding mechanism illustrated in Fig. 1; and

Fig. 5 is a detail sectional view taken along line V—V of Fig. 3.

Referring to the drawings, I have illustrated an electrode mounting consisting essentially of a suitable base 1, to the underneath surface of

which may be attached a driving motor 2, the motor being secured to the plate 1 in any suitable manner as by means of bolts 3.

Rising from the base 1 is a positive electrode support consisting of a bearing bracket 4, to which is secured a positive electrode head 5. By referring particularly to Fig. 3, it will be observed that the electrode head 5 has a pair of horizontally extending openings 6 and 7, the opening 6 receiving the electrode supporting sleeve or carrier 8, through which the positive carbon electrode 9 projects. The sleeve 8 is mounted in the opening 6 for rotation therein, as by means of a pair of ball bearings 10 and 11 frictionally held within the interior of the opening 6. The bearings 10 and 11 are spaced apart longitudinally of the opening 6 by means of a spacer 12 secured in place in the head 5 by means of a set screw 13.

The rear end of the electrode sleeve 8 is provided with a beveled gear 14 meshing with a beveled gear 15 secured upon the upper end of a drive shaft 16, which is in turn connected as by means of an insulating coupling 17, the shaft 18 extending through vertically aligned bearings in the bracket 4, the lower end of the shaft 18 being connected as by means of gears 19 and 20 to a shaft 21 driven by the motor 2.

Thus during the entire operation of the motor 2 the electrode sleeve 8 will be rotated to thereby rotate the positive carbon electrode 9. The rotary movement of the sleeve 8 is transmitted to the electrode 9 by means of a flange 22 formed upon the forward end of the sleeve 8, this flange having a pair of radially extending recesses 23 and 24 on diametrically opposite sides of the electrode 9, in which slots or recesses operate a plurality of spur gear assemblies 25 and 26. Each of the spur gear assemblies 25 and 26 is preferably formed as a pair of relatively thin disc-like members 25a and 25b preferably formed integrally with an under-cut peripheral slot 25c separating the teeth of the gear to thereby form in effect a pair of relatively thin spaced spur gears, the teeth of which will engage and grip the electrode 9 at spaced points. By mounting the spur gear assemblies 25 and 26 on diametrically opposite sides of the electrode 9, it will be apparent that four distinct points of contact between the spur gears and the electrode are achieved.

The extreme outer end of the sleeve 8 is provided with a forwardly projecting wing member 27, which member is provided with a pair of radially extending slots 28 and 29, in which are slidably supported a pair of pin shafts 30 and 31. The pin shaft 30 constitutes the bearing upon which the gear assembly 25 is supported while the shaft 31 performs a similar function for the gear assembly 26. By interconnecting the outer ends of the pin shafts 30 and 31 by means of relatively light springs 32 and 33, the spur gear assemblies are yieldingly urged into gripping relation with the electrode 9. Thus rotation of the sleeve 8 is transmitted through the spur gear assemblies 25 and 26 acting as a clutch or grip on the electrode 9.

The forward and rearward movement of the electrode 9 within the sleeve 8 is controlled by rotating the spur gear assemblies 25 and 26 about their pin shafts 30 and 31. This is accomplished by mounting a disc-like gear member 34 upon the exterior of the sleeve 8 so as to be rotatable relative to the sleeve 8. I prefer to form a bearing surface 35 on the sleeve 8 by slightly enlarging the diameter of the sleeve 8 immediately at the rear of the flange 22.

The disc-like gear 34 is provided upon its forward face with spiral or scroll gear teeth 36 adapted to engage the teeth of the spur gear assemblies 25 and 26. Thus if the scroll gear member 34 is rotated about the longitudinal axis of the electrode 9 at any speed different from the speed of rotation of the sleeve 8, the relative motion between the spur gears 25 and 26 and the scroll gear 34 will cause the spur gears 25 and 26 to rotate about their pin shafts to move the electrode 9 forwardly or rearwardly, depending upon the ratio of such speed difference.

In order to insure the steady intensity of the light produced from an arc lamp, the positive carbon should be fed into the arc continuously at a rate of speed equal to the speed at which the extreme end of the carbon is burned away. If the forward feeding of the carbon 9 is intermittent, there will be a considerable fluctuation in the arc and a considerable variation in the intensity of the arc immediately before and immediately after the forward feeding movement is accomplished. However, if the carbon 9 is fed forwardly with a steady and continuous non-intermittent motion at the proper rate of speed, the arc will burn steadily with a relatively unvarying intensity. It is this latter condition which is most desirable in photographic work since any variation in intensity of the light upon the object will cause the photographic film to register images of varying density, producing an unsatisfactory result.

With the construction hereinbefore described, a steady forward feeding of the electrode 9 may be readily accomplished by rotating the scroll gear 34 at the proper difference in speed relative to the speed of rotation of the electrode 9 about its axis.

The driving motion for the scroll gear 34 may be readily transmitted thereto from the same driving force which rotates the carbon 9, as by mounting a secondary sleeve 37 for rotation in the second opening 7 on the head 5. The sleeve 37 may be mounted upon suitable spaced ball bearings 38 and 39 in parallel relation with the sleeve 8. The forward end of the sleeve 37 extends radially as a flange 40, upon the periphery of which are cut spur gear teeth 41 adapted to mesh with a spur gear 42 fixedly mounted upon the sleeve 8, as by means of a keyway 43 formed in the gear 42 engageable with an outwardly projecting pin 44 secured to the sleeve 8. The flange 40 has its forward surface engaged with the rear surface 45 of a small gear 46 so as to cause the gear 46 to be frictionally coupled to the flange 40. The gear 46 is rigidly secured as at 47 to a rearwardly extending shaft 48 having a shoulder or collar 49 formed thereon serving as an abutment for a spring 50, the opposite end of which engages the rear face of the clamping nut 51 held in place by a set screw 51a and retaining the assembly mounted on sleeve 37 so as to exert a continuous rearward pressure upon the gear 46 to insure frictional engagement between the gear 46 and the flange 40.

The gear 46 is meshed with spur gear teeth 52 on the periphery of the scroll gear 34 so that rotation of gear 42 by the sleeve 8 will be transmitted through the flange 40 and gear 46 to the scroll gear 34. By selecting the diameters of the gear 42, the flange 40, the gear 46 and the scroll gear 34, any desired ratio of speed may be obtained between the speed of rotation of the sleeve 8 and the scroll gear 34. I prefer, however, to

select the gear ratios such as to cause the scroll gear 34 to rotate at a slightly lesser speed than the sleeve 8, thus using the differential between the two speeds to achieve the forward driving movement of the spur gears 25 and 26 though it will be understood by those skilled in the art that by arranging the gear 35 to rotate at an increased speed over that of the sleeve 8, the same effect may be accomplished by changing the direction of the spiral teeth 36 on the scroll gear 34.

By employing the friction coupling between the flange 43 and the gear 46, it will be apparent that the scroll gear 35 may be rotated in one direction or the other independent of the movement of the sleeve 8 to achieve the initial adjustment of the electrode 9 or to make rapid adjustments in the position of the electrode 9 if and when such may be desired. The shaft 48 may be coupled, as indicated at 60, to a manual shaft 61 extending to any desired position and provided with any suitable handle, not shown, by which the gear 39 may be manually rotated, and the positive rotating carbon fed forward or backward as desired while the rotation of the same is undisturbed by the manual adjustment during operation.

As will be understood by those skilled in the art, various parts of the mechanism are insulated from each other in the manner well known in this art so as to isolate the various components from each other with respect to the currents carried by them.

As is usually desired in arc lamps of this character, the negative electrode 62 may be continuously and automatically fed toward the positive electrode 9 as the negative electrode is burned away by mounting the negative electrode 62 in a suitable carriage 63, which is in turn mounted upon a threaded shaft 64 journaled upon a negative electrode head 65. The shaft 64 is preferably slidably mounted, as well as rotatably mounted, in its bearings 66 and 67 so that a rapid upward movement of the negative electrode 62 may be accomplished by a bell crank 68 pivoted upon the head 65, as indicated at 69, and engaging a collar 70 on the threaded shaft 64. Thus movement of the bell crank 68 above its pivot 69 will lift the entire shaft 64 and the carriage 63 to move the electrode 62 into engagement with the projecting end of the electrode 9 whenever it is desired to strike the arc.

The shaft 64 may be provided with a bevel gear 71 meshed with a bevel gear 72 connected to a shaft 73 which is in turn geared as indicated at 74 to a worm wheel 77 driven by a worm 78 on the main drive shaft 13, the worm wheel 77 being frictionally or mechanically or by means of a throw out clutch coupled as indicated at 79 to the gearing 76, permitting manual movement of the shaft 73 independent of the drive shaft 13 through the agency of an adjusting shaft 80 whenever such adjustment is desired.

Again it will be understood by those skilled in the art that while illustration and description of the electrical circuits leading to the electrodes has been omitted herein, the usable circuit arrangement supplying current to the two electrodes with a ballast resistance interposed therein may be employed and that the motor 2 will be connected in shunt relation to the electrodes in such manner that the motor will operate at a speed corresponding to the voltage across the arc, thereby achieving the feeding of the carbon in

correspondence with the rate at which the carbon is burned away.

It will therefore be observed that I have provided an arc lamp in which the positive carbon may be mounted horizontally and may be rotated at any desired speed best adapted for maintaining the most effective crater condition in electrode 9 for the most advantageous production of light and the production of the particular light values desired, while the rotary motion of the carbon is employed for longitudinally feeding the carbon at a rate proportional to the rate at which the carbon is consumed, which longitudinal feeding will be steady, even and continuous during the entire operation of the lamp and which permits the necessary manual adjustments of the carbon position without interfering with the longitudinal feeding thereof.

While I have shown and described the preferred embodiment of my invention, I do not desire to be limited to any of the details listed and described herein except as defined in the appended claims.

I claim:

1. In an arc lamp, an electrode, a rotatable electrode carrier for carrying said electrode for rotation about its longitudinal axis, electrode feeding means engaging said electrode, means mounting said feeding means on said carrier for rotation in the direction of the longitudinal axis of said electrode axis, a scroll gear rotatable on said electrode carrier and meshed with said feeding means, and gear means interposed between said carrier and said scroll gear to continuously and non-intermittently rotate said scroll gear by rotation of said carrier but at a speed different from that of said carrier.

2. In an arc lamp, a positive electrode, a negative electrode, a rotatable carrier means mounting said positive electrode for rotation about its longitudinal axis relative to the negative electrode, means for longitudinally moving said positive electrode including rotatable electrode engaging means, means mounting said engaging means for rotation in the direction of the longitudinal axis of said electrode, a scroll gear associated with said electrode engaging means for rotating the same, and gear means interposed between said scroll gear and said carrier means for continuously coupling said scroll gear to said carrier means non-intermittently for rotating said scroll gear at a different rate of speed from that of said electrode mounting means.

3. In an arc lamp, a pair of electrodes, a rotatable sleeve through which one of said electrodes projects, a pair of gear members carried by said sleeve, means mounting said gear members for rotation in the direction of the longitudinal axis of said electrode, a scroll gear rotatable about said sleeve and meshed with said gear members, and gear means interconnecting said scroll gear with said sleeve for continuous, nonintermittent rotation at a speed different from the speed of rotation of said sleeve.

4. In an arc lamp, a pair of electrodes, a rotatable sleeve through which one of said electrodes projects, a plurality of gear members carried by said sleeve on radially opposed sides of said electrode for engaging said electrode to feed the same, means mounting said gear members for rotation in the direction of the longitudinal axis of said electrode, a scroll gear rotatably mounted upon said sleeve and meshed with said gear means, means for rotating said sleeve, and gearing interposed between said sleeve and said scroll gear to continuously and non-intermittently rotate

said scroll gear at a speed different from the speed of rotation of said sleeve.

5. In an arc lamp, a pair of electrodes, a rotatable sleeve through which one of said electrodes projects, a pair of gear members carried by said sleeve on diametrically opposite sides of said electrode for engaging said electrode to feed the same, means mounting said gear members for rotation in the direction of the longitudinal axis 10 of said electrode, a scroll gear rotatably mounted upon said sleeve and meshed with said gear means, means for rotating said sleeve, a gear rigid with said sleeve, a shaft parallel with said sleeve having a gear meshed with said sleeve 15 gear, and a second gear on said shaft for continuously non-intermittently driving said scroll gear at a speed differing from the speed of rotation of said sleeve.

6. In an arc lamp, a pair of electrodes, a rotatable sleeve through which one of said electrodes projects, a pair of gear members carried by said sleeve on diametrically opposite sides of said electrode for engaging said electrode, means mounting said gear means for rotation in the direction 20 of the longitudinal axis of said electrode, a spur gear having a scroll gear on one of its faces, means mounting said scroll gear on said sleeve for rotation relative thereto, a gear fixed to said sleeve, and gearing interposed between said fixed gear and said scroll gear for continuously and 25 non-intermittently rotating said scroll gear by rotation of said sleeve at a speed differing from the speed of said sleeve.

7. In an arc lamp, a pair of electrodes, a rotatable sleeve through which one of said electrodes projects, an end flange on said sleeve extending radially at one end thereof, a pair of gear members for engaging said electrode, means mounting 5 said gear members on the end flange of said sleeve for rotation in the direction of the longitudinal axis of said electrode, a scroll gear rotatably carried by said sleeve immediately to the rear of said flange and meshed with said gear 10 means, and means interposed between said scroll gear and said sleeve for continuously and non-intermittently rotating said scroll gear at a speed differing from the speed of said sleeve.

8. In an arc lamp, a pair of electrodes, a rotatable sleeve through which one of said electrodes projects, an end flange on said sleeve extending radially at one end thereof, a plurality of slots 15 in said flange disposed about said electrode and extending radially thereof, a plurality of gear 20 members carried on the front of said flange and extending through the slots, means mounting said gear members on said flange for rotation in the direction of the longitudinal axis of said electrode, a scroll gear rotatably mounted on said sleeve immediately at the rear of said flange and meshed with said gear members at the rear of said flange, and gearing interposed between said scroll gear and said sleeve for rotating said scroll gear 25 at a speed differing from the speed of said sleeve. 30

ELMER C. RICHARDSON.
